Patented May 8, 1917.

FIG. 3

William S. Cutting, Inventor
By his Attorney
Robert E. Fuller.

UNITED STATES PATENT OFFICE.

WILLIAM S. CUTTING, OF ONAWAY, MICHIGAN.

RAILROAD-SPIKE.

1,225,589.

Specification of Letters Patent.

Patented May 8, 1917.

Application filed January 26, 1916. Serial No. 74,505.

To all whom it may concern:

Be it known that I, WILLIAM S. CUTTING, a citizen of the United States, and resident of Onaway, in the county of Presque Isle 5 and State of Michigan, have invented certain new and useful Improvements in Railroad-Spikes, of which the following is a specification.

This invention relates to railway rail 10 spikes, and one of the principal objects of the invention is to provide simple, reliable and efficient means for preventing the rail from loosening the spike.

Another object of the invention is to provide a rail spike which, when driven into the rail tie almost the entire distance, will automatically operate a pivoted member which is caused to assume a horizontal position in the tie when the spike is fully driven 20 and preventing the easy removal thereof.

These and other objects may be attained by means of the construction illustrated in the accompanying drawing, in which,

Figure 1 is a front view of an undriven 25 spike. Fig. 2 is a vertical sectional view on the line 2—2 of Fig. 1. Fig. 3 is a sectional view, reduced in size, of a rail tie and rail illustrating the manner of application of this spike thereto.

Similar characters of reference refer to 30 similar parts throughout the several views.

Referring to the drawings, the numeral 4 designates the main body of this rail spike and which has the usual head 5 and wedge 35 point 6. On that side of the spike which adjoins the rail when driven, a rectangular recess 7 is formed. A stop pin 8 and an additional pin 9 are fastened or riveted to the opposite walls of the recess 7 as shown.

The pin 9 forms a pivot for the bayonet, 40 the bayonet being centrally positioned in the opening 11 of the bayonet operating member 12.

The upper part 13 of the member 12 is 45 bent transversely so as to conform to the flange of the rail 14 and to the lower portion of the spike head 5. The member 12 is prevented from ordinary dislodgment by means of the pin 8.

The operation of this spike is now as follows: When driving, the spike and parts 50 thereof are in the position illustrated by the full lines in Figs. 1 and 2. It will be noticed that, in this position, there is no impedi-

ment in the way of either driving or extracting the spike from the tie 15. The spike is now driven in the usual manner. When the spike is driven a sufficient distance so that the part 13 contacts with and is stopped by the flange of the rail 14, as 60 will readily be understood, the next stroke of the driving hammer will nevertheless cause the spike to be driven still farther into the tie but will incidentally, on account of the impossibility of the downward movement of the member 12, cause the bayonet 10 to be forced outwardly from the recess 7 into the tie 15, as is clearly indicated by the dotted lines in Fig. 2. To explain this action more fully, it will be noticed that 70 part of the rear side 16 of the spur 10 is in angular relation with the extreme lower portion of the member 12. Driving the spike beyond the normal depth of the part 13 will have a corresponding effect to pulling the 75 member 12 upward as shown by the dotted lines in Fig. 2. This action will cause the spur 10 to swing on its pivot 9, the bayonet assuming an approximately horizontal position in the tie as will be readily understood. 80 It will now be apparent that, should any external force be upwardly applied to the spike, there will be more than ordinary resistance offered by the spike owing to the fact that the spur 10 would retain its horizontal position, thereby offering a large 85 amount of resistance to any upward movement of the spike.

From the foregoing it will be obvious that a rail spike made in accordance with this 90 invention is extremely simple in construction, will prevent the action of trains over the rail from loosening the spike and will thereby prevent numerous accidents.

Various changes may be made in the details of construction without departing from 95 the spirit and scope of the invention as defined in the claims.

What is claimed is:—

1. A rail spike having a longitudinal recess therein, pins mounted in the walls of said recess, a spur pivoted upon one pin and normally positioned within the recess, a longitudinally movable member retained in the recess by one of said pins and slotted 100 to receive said spur, one end of the slot being adapted, as the member is moved longitudinally in one direction, to impinge 105

against the edge of the spur to throw the same to a position at right angles to the length of the spike.

2. A rail spike having a longitudinal recess therein, pins mounted in the walls of said recess, a longitudinally movable member retained within the recess by one of said pins and provided with a curved slot, one end of the member being outwardly bent, 10 a spur pivoted upon one pin and extending

through said slot and having a portion of its rear edge inclined, adapted to bear against the end of said slot.

Signed at Onaway, in the county of Presque Isle, and State of Michigan, this 15 24th day of January, A. D. 1916.

WILLIAM S. CUTTING.

Witnesses:

OTTO L. WICKERSHAM,
NELLIE FOX.
